[57] CLAIM

The ornamental design for a translucent interlocking panel member for ceilings or the like, as shown and described.

DESCRIPTION

FIG. 1 is a perspective view of the panel member, viewed from below;

FIG. 2 is a top plan view of the panel member;

FIG. 3 is a bottom plan view;

FIG. 4 is a front elevation; and

FIG. 5 is a side elevation of the panel member taken from the left side of FIGS. 1, 2 and 3. The rear of the panel member is identical to the left side, and the right side is identical to the front.
